BACTERIURIA TEST DEVICE

Donald P. Kronish, Rockaway, and Lee S. Zuriff, Parsippany, N.J., assignors to Warner-Lambert Pharmaceutical Company, Morris Plains, N.J.

Filed Mar. 25, 1970, Ser. No. 22,047

Term of patent 14 years

Int. Cl. D24—02

U.S. Cl. D16—1

FIG. 1 is a perspective view of a bacteriuria test device showing our new design.

FIG. 2 is an exploded view of FIG. 1.

FIG. 3 is a front elevation of the paddle member.

FIG. 4 is a side elevation thereof.

FIG. 5 is a cross-section taken on line 5—5 of FIG. 3.

FIG. 6 is a cross-section taken on line 6—6 of FIG. 3.

FIG. 7 is a front elevation of a second modified embodiment of the paddle member illustrated in FIG. 3.

FIG. 8 is a side elevation thereof.

FIG. 9 is a cross-section taken on line 9—9 of FIG. 7.

FIG. 10 is a front elevation of third modified embodiment of the paddle member illustrated in FIG. 3.

FIG. 11 is a side elevation thereof.

FIG. 12 is a cross-section taken on line 12—12 of FIG. 10.

FIG. 13 is a front elevation of fourth modified embodiment of the paddle member illustrated in FIG. 3.

FIG. 14 is a front elevation of a fifth modified embodiment of the paddle member illustrated in FIG. 3.

FIG. 15 is a side elevation thereof.

FIG. 16 is a front elevation of a sixth modified embodiment of the paddle member illustrated in FIG. 3.

FIG. 17 is a cross-section taken on line 17—17 of FIG. 16.

FIG. 18 is a cross-section taken on line 18—18 of FIG. 21.

FIG. 19 is a cross-section taken on line 19—19 of FIG. 22.

FIG. 20 is a cross-section taken on line 20—20 of FIG. 16.

FIG. 21 is a front elevation of a seventh modified embodiment of the paddle member illustrated in FIG. 3.

FIG. 22 is a front elevation of an eighth modified embodiment of the paddle member illustrated in FIG. 3.

We claim:

The ornamental design for a bacteriuria test device, substantially as shown and described.
